UNITED STATES PATENT OFFICE.

ROBERT W. BARKER, OF PROVIDENCE, RHODE ISLAND, ASSIGNOR TO EDWARD A. TAFT,
TRUSTEE, OF BROOKLINE, MASSACHUSETTS.

KNOT-TYING IMPLEMENT.

Application filed February 7, 1918, Serial No. 215,789. Renewed September 3, 1920. Serial No. 408,053.

To all whom it may concern:

Be it known that I, ROBERT W. BARKER,
a citizen of the United States, residing at
Providence, in the county of Providence
5 and State of Rhode Island, have invented
certain new and useful Improvements in
Knot-Tying Implements, of which the fol-
lowing is a specification.

The principal object of this invention is to provide an implement for joining two threads or strands by tying therein a knot known as a "weaver's knot", or substantially such a knot. The weaver's knot, as shown Figure 25 of the accompanying drawings, is a knot characterized by two loops (one in each strand) of which one passes through the other loop and has the strand of the latter loop passed through it and the free end of such strand interposed between it and said strand. Such a knot is preferred by weavers and others having occasion to draw the connected strands through restricted openings, as the spaces between the dents of a loom reed, because it is best adapted to pass through such openings without catching and with the least danger of breaking or injuring the strands.

In the accompanying drawings,

Figure 1 is a front elevation of the implement shown held by the hand of the operator, ready for tying a knot:

Figures 2 to 6 are views of the implement on a larger scale and showing all the parts in the position preparatory to tying a knot, Figure 2 being a front elevation; Figure 3 a right side elevation; Figure 4 a rear elevation, Figure 5 a left side elevation and Figure 6 a plan;

Figure 7 is a front elevation of the implement with the main rocking shaft d and the following parts carried thereby, to wit, the main operating handle m , segment n , and front or swinging crotch member h , removed;

45 Figures 8 and 9 are rear and side elevations of said member h with a certain lever z removed therefrom;

Figure 10 is a side elevation of the combined strand separator and strand clip:

50 Figures 11, 12 and 13 are side elevations of the aforesaid lever and segment and a certain transmission pinion:

Figure 14 is a side elevation, partly in section, of the tubular mounting 8 and pinion 9 for the knotting bill.

Figures 15 and 16 are inside elevations of the two sections of the knotting bill, these views also showing end elevations of said sections and Figure 15 showing the moving jaw of the knotting bill;

Figure 16^a is a sectional view of the working end of the knotting bill;

Figure 17 shows in longitudinal section and end elevation the cam for controlling said jaw; 65

Figure 18 shows the stationary knife in front and side elevation;

Figures 19 and 20 are fragmentary views on a larger scale respectively showing the implement in side elevation, partly in section on line 19—19 of Figure 2, and in horizontal section on substantially line 20—20 of the same figure;

Figures 21-24 show the knot-tying operation by successive steps; and

Figure 25 shows the finished knot.

Referring, first, to Figures 19-25: A cross is made in the strands, by means to be explained, of such character that each strand crosses and re-crosses the other; the specific arrangement, shown best by the plan views of the cross (Figures 20 and 21), involves strand A extending from the right of strand B (as the implement is held in operative position in the user's hand, Figure 1), over and under strand B back to the right.

As will be explained, the knotting bill, rotative on a horizontal axis, has its free end turned off and tapered, being also split to form counterpart turned-off tapered halves between which is fulcrumed a jaw which ultimately coacts with the bill to sever one of the strands (B) and hold it for drawing tight the knot. The bill rotates in the direction of the arrow in Figure 19, its starting position being, as there shown, where the bill projects rearwardly and downwardly, underlying the rear V of the cross. Figure 22 shows the knotting bill after it has performed somewhat more than three-fourths of a revolution, its tapered end or point having first entered the rear V of the cross, then the forward V, and so formed the loop A' (see also Figure 25). The jaw 13 of the bill, at first wholly sheathed between the halves of the bill as it appears in Figure 24, is in this position more or less open, standing between loop A' and the free end of the bill. When the

bill has completed somewhat more than a full revolution, a lever arm 28 has moved the strand A to the right of the free end of and across the bill (Figure 23) so that 5 said strand, on further rotation of the bill, will not lie between the jaw 13 and the bill and be cut and held thereby. Strand B, however, remains vertically overlying the space between the open jaw and bill, so 10 that when the bill has completed about a one and one-quarter revolution and the jaw is then closed it will be cut and held by the coaction of said jaw and the bill, now ensuing. The thus-cut end of strand B must 15 now be passed first under the two parts of strand A extending from its loop A' and then between the loop and strand B, as in Figure 25, to form loop B'. This is accomplished by slipping the noose or cinc- 20 ture which has been formed on the knotting bill off the same onto strand B (still held at its severed end by the knotting bill) thus: While the bill is turning another quarter-revolution to its limit (pointing 25 forward) certain means begins to operate to draw forward on the two strands (strand A having been meanwhile severed at a point behind the bill), which results in said cinc- 30 ture being slipped off onto the end portion of strand B held by the bill and finally drawn tight, developing the desired knot.

The foregoing outline of the knot-tying will facilitate an understanding of the mechanisms involved, now to be described:

35 There is a blade-shaped frame *a* having rearwardly projecting bearing ears *b* and its upper portion set back, by a bend *a'*, out of the plane of its lower portion, and also having at the left upper side a forward 40 vertical wall *c*. The main shaft *d* is journaled in ears *b* and on this shaft is pivoted an eye-piece *e* through which and an eye *f* on the lower end of the frame a strap *g* may be passed for buckling the implement on the 45 left hand of the user, as shown by Figure 1.

h is a blade-like member having its upper end bent rearward, its lower end having rearward ears *i* which project through slots *j* in the frame *a* (Figure 2) and are 50 penetrated by shaft *d*, on which member *h* is thus fulcrumed. On its left side is a rearward arm *k* having a lateral pin *l* (Figures 8 and 9). The main shaft has fixed 55 to its right and left ends, respectively, the operating arm or handle *m* and a segment *n*, the segment having an arc-shaped slot *o* receiving pin *l* and thus permitting some lost motion of the segment to ensue in either direction before member *h* is turned there- 60 by on its fulcrum. The upward limit of movement of the parts (closed or starting position) is determined by contact of member *h* with member *a* and the forward end of slot *o* with pin *l*; the downward limit 65 (open position) by contact of the rear end

of said slot with the pin and of the member *h* with the lower end of the left-hand slot *j* in frame *a*.

The upper end of the frame is formed with a crotch *p* (Figure 7) having convex 70 sides, the narrowest part of the crotch being about midway, transversely, of the blade; the crotch communicates downwardly with an opening *q* which reaches to the right. The device shown best in Figure 10 (see 75 also Figure 4), consisting of a plate *r* having a rearwardly extending forked clip *s* and its top forming a horizontal table *t*, and having rising from said table a vertical forwardly canted separator blade *u* with 80 a depending laterally offset spring detent *v*, is secured to the back of the frame *a* by a screw *w* in such manner that the separator bisects the crotch *p* and the table reaches to the right. Member *h* likewise 85 has a crotch *x* (Figures 2 and 8) having convex sides, the narrowest part of the crotch being offset somewhat to the right of said member, so that the narrowest parts 90 of the crotches *p* and *x* are unopposed or offset with respect to each other; the crotch *x* communicates downwardly with an opening *y* which reaches to the left (Figure 2). A lever *z* (Figures 2, 3 and 11) is ful- 95 crumed at 2 on the member *h* and its upper 100 end portion reaches from a point near the left hand end of the opening *y* upward and to the right, its edge *z'* forming a convex curve and crossing the opening and the crotch; this lever has but slight movement limited by engagement of its lugs 3 and 105 4 with the right side of member *h* and the left side of right hand slot *j*, respectively. To form the cross the two strands (mem- 110 ber *h* being in fully closed position) are held by the fingers of the operator's left hand (dotted lines, Figure 1) pressing against the flat front face of the frame *a*, his right hand being used to separate the strands by means of the separator *u* (see 115 the upwardly extending dotted lines in Figure 1, showing the strands in the act of being separated) and then carry their free ends down back of the implement into the grip of the clip *s*. It may be here remarked that between a presser foot 5 of lever *z* and an anvil 6 on the frame (which coact to grip the strands and thereupon strip the cincture off the knotting bill) a notch will be formed to receive the strands. Further, when the im- 120 plement is closed, the spring detent *v* of the separator bears against the left side of the crotch *x*. The operation of entering the strands into the crotches involves, as to the member *h*, the strand (A) at the left of the separator being stopped against further descent by the detent *v* where the detent 125 impinges against the left side of the crotch *x*, and the strand B passing down into the 130

opening y , into which it is deflected by the edge z of lever z , the two strands lying together in the notch between 5 and 6; as to the member a , the entering operation 5 involves strand A, which enters crotch p at the left of the separator, shifting to the right in opening q under the table-forming portion t (because strand receiving clip s is somewhat offset to the right of the implement, Figure 6) and strand B, which is at the right side of the separator, coming to rest on the table t . On a view to Figures 20 and 21, and particularly Figure 20, it will be seen that in the final position of 10 the strands strand B has undergone relatively little deflection as to the cross formed, but strand A reaches to the left, from the point where its downward descent was stopped by the detent, and over and around 15 strand B and then back to the right. A cross is thus formed of the kind already described, the rearward and forward V's of which are indicated in Figure 20 by X' and X'' , respectively.

20 Screwed into the wall c is a long bearing 7 in which is journaled a sleeve 8 formed at its inner end with a pinion 9. The two sections 10 and 11 of the knotting bill are secured in this sleeve by a pin passed 25 through the holes 12 in these three parts. The free ends of the sections are tapered and turned off, and the edge 10' of the section 10 is dull and the edge 11' of section 11 beveled to a shear edge or knife. 30 Fulcrumed in the slit between and conforming in side elevational shape to the end portions of the sections 10-11 is a jaw 13 having a T-shaped head 14 at its inner end. The jaw has its convex edge at one side 35 (next bill section 11) beveled to a shear edge and at the other side rounded or dull. It will be seen by Figure 16^a that if a strand 40 is interposed between the ends of the bill sections and the open jaw and the jaw then closed the strand will be sheared off by 45 11 and 13 and pinched between and thereby gripped by 10 and 13. The point or 50 free end of the bill rotates in a vertical plane bisecting the V's, X' , X'' , of the cross.

55 Revoluble on the bill between pinion 9 and the head 14 of the jaw is a cam 15 whose cam surface bears against said head, the same having an arm 16 permitting, by its contact with the stops 17 and 18 (Figure 7), the cam to perform only a part of a revolution. Because the cam abuts the pinion on the one hand and head 14 of the jaw 13 on the other the cam will turn with the bill until its rotation is checked by one of these stops, whereupon it will obviously cause the jaw to oscillate. On a stud 19 60 back of bearing 7 is journaled a transmission pinion 20 which meshes with pinion 9 and has on its hub a flat 21 (Figure 13).

The segment n has a segmental series of teeth 22 which mesh with the teeth of the pinion 20. When the segment is swung forward it transmits rotary motion through pinions 20 and 9 to the knotting bill; the 70 segmental teeth 22 in the forward movement of the segment clear the transmission pinion before the said movement of the segment is complete, and for holding the knotting bill against turning during the remainder of 75 such movement a shoe or plate 23, having its outer face concentric with the shaft d , thereupon opposes such outer face to the flat 21 on pinion 20, sliding over the same. As best shown in Figure 2, the periphery 80 of the segment overlaps pinion 9 to prevent inward displacement of said pinion and its sleeve 8 out of bearing 7.

A U-shaped plate 24 (Figure 18) having an upstanding shearing edge or knife 25 is 85 secured to the frame a so that its shearing edge is just to the right of opening q (Figure 7); fulcrumed in the plate is a bell-crank lever one arm 26 of which engages in a cam slot 27 in the segment n and the 90 other arm 28 of which oscillates in shearing relation to the edge 25 and is preferably beveled (Figures 21 to 24) to cooperate therewith in shearing.

When the lower end 4 of the hereinbefore 95 mentioned lever z is at either end of slot j said lever is free, said ends of the slot having recesses 29 to afford the necessary clearance; but when member h is between its limits of swinging movement, and consequently said end 4 of lever h is between the ends of the slot, the left side of the slot forces the lower end of the lever to the right, so that at 5 it will press the strands 100 against the anvil 6 and so grip them. The 105 left side of slot j therefore constitutes a cam for actuating the lever.

Operation: In turning the handle to the dotted line position, Figure 3, the segment n , as the rear of slots o engages stud 7, picks 110 up and moves the crotched member h to dotted line position of Figure 3. This is the working stroke of the parts. In the return stroke the handle and segment move back idly till the forward end of slot o 115 abuts stud 7, when the crotched member h is carried back to the closed or starting position. The manner of forming the cross has been already explained. As soon as the crotched member h begins to move forward 120 with the segment n in the working stroke lever z is moved by the cam side of slot j to grip the forward end of the two strands between 5 and 6, thus to draw them forward; at the back of the implement they 125 are held by the clip s . This drawing on the forward ends of the two strands ultimately effects stripping of the cincture off the knotting bill that has been formed thereon during the forward movement of member h 130

and thereupon the drawing of the cincture tight into a knot after strand A has been severed by 28—25 and while strand B, previously severed, is still gripped by the knotting bill, and finally the clearing of the united strands from the bill by withdrawing strand B from the grip thereof. After such clearance, and as soon as the cam side of slot *j* ceases to act on lever *z* (forward position of member *h*) the united strands may be readily removed from the crotch in member *h*.

The gearing connecting the bill and segment *n* causes the former to start rotating immediately upon depressing the handle; the rotation continues (the bill turning in all somewhat more than $1\frac{1}{2}$ revolutions) well after the member *h* begins to advance, stopping as soon as gear teeth 22 leave the pinion 20, whereupon the latter and bill are held fixed by shoe 23 engaging flat 21 of said pinion. Cam 15 (on account of its arm playing between the spaced stops 17—18) can rotate but a relatively short distance with the bill, which, due to the frictional engagement of its jaw head 14 and pinion 9 with the cam, carries the cam around until it is arrested by stop 17; the cam thus stopping, the continued rotation of the bill obviously effects opening and closing movement of the jaw. (In the previous resetting of the parts after tying a knot cam arm 16 was left impinging against stop 18, having closed the jaw.) The opening of the jaw begins after the bill point has well entered first the V marked X' and then the V marked X'', and the jaw is more or less fully open, holding loop A', which has been formed, on the bill, at about the position of the bill in Figure 22. In Figure 23 the bill has advanced another quarter revolution, and the jaw still holds the loop A' on the bill. As the bill continues rotating from this position the jaw is closing, and about 45 when the bill projects upward the jaw co-acts with the sections of the bill first to sever and then to grip the strand B. While the bill is now turning forward member *h* draws forward on the strands (strand A having been severed, as will be explained) so that the cincture formed begins to be stripped from the bill. The bill now stops rotating—due to shoe 23 engaging flat 21 of pinion 20—and the still moving member *h* draws the cincture clear of the bill and, as the latter still grips the severed end of strand B, pulls the cincture tight to form the knot and finally withdraws said strand end clear of the grip of the bill.

60 The movement of lever 26—28 in response to cam-slot 27 begins as soon as segment *n* starts to move, and its arm 28 is clear and to the right of the point of the bill, holding strand A across the bill and its jaw, in the 65 position of the parts shown by Figure 23.

Said lever remains then practically without motion until after strand B has been severed and just before the cincture is to be stripped from the bill, whereupon cam slot 27 again moves it to the right so that arm 28 70 and knife 25 coact to sever strand A. Strand A is allowed to relax sufficiently so as not to tauten and offer resistance to the displacing influence of lever arm 28, because immediately member *h* cleared 75 detent *v* the stop offered by the latter to the descent of said strand of course failed and the strand fell into opening *y*, slack.

It will be seen on reference to Figures 21 to 23 that in tying such a knot, in particular, as has been hereinbefore specified (a weaver's knot) though the mechanism shown actually develops the loop A', the tying or knotting bill in effect passes a part of one strand (as B) near the cross around both 80 parts of the other strand (as A) near the cross and between the first strand and said parts of the other strand—compare figure 25—in the actual adaptation illustrated and described having already severed said first 90 strand (B).

As to the strand-cross forming part of my invention, this involves strand checks (as table *t* on the one hand and that afforded where detent *v* abuts one side of crotch *w*) 95 arranged one forward of the other and against which the strands are respectively adapted to bear, means to guide the strands to the checks, and clearance afforded one strand (as opening *y* or *q*) for displacement 100 laterally under the check for the other strand: in the actual form set forth, where one strand is made to cross and recross the other, such clearance is afforded each strand.

Having thus fully described my invention, what I claim as new and desire to secure by Letters Patent is:—

1. A strand-cross-forming instrumentality having strand checks arranged one forward of the other and against which the respective strands are adapted to bear, said instrumentality having means to guide the strands against said checks and affording clearance to one strand to be displaced laterally under the check for the other strand. 115

2. A strand-cross-forming instrumentality having strand checks arranged one forward of the other and against which the respective strands are adapted to bear, said instrumentality having means to guide the strands against said checks and affording clearance to one strand to be displaced laterally under the check for the other strand and also having means to cause such lateral 120 displacement of said strand.

3. A strand-cross-forming instrumentality having strand checks arranged one forward of the other and against which the respective strands are adapted to bear, said instrumentality having means to guide the 130

- strands against said checks and affording clearance to each strand to be displaced laterally under the check for the other strand.
4. A strand-cross-forming instrumentality having strand checks arranged one forward of the other and against which the respective strands are adapted to bear, said instrumentality having means to guide the strands against said checks and affording clearance to each strand to be displaced laterally under the check for the other strand and also having means to cause such lateral displacement of said strand.
5. A strand-cross-forming instrumentality including a separator for the strands and a crotched device having means, on separating the strands by the separator and entering them into said device, to permit one strand to be displaced into crossing relation to the other.
6. A strand-cross-forming instrumentality including a separator for the strands and a crotched device having means, on separating the strands by the separator and entering them into said device, to permit each strand to be displaced into crossing relation to the other.
7. A strand-cross-forming instrumentality including a separator for the strands and a crotched device having means, on separating the strands by the separator and entering them into said device, to deflect one strand into crossing relation to the other.
8. A strand-cross-forming crotched device having means on entering the strands thereinto to deflect the strands each under the other at different points, whereby to produce a crossing-over and crossing-under of one strand relatively to the other.
9. The combination, with the frame, of a rotary tying bill having a movable jaw coactive therewith to grip a strand, means to rotate the bill, and a cam for controlling said jaw friction-moved by and with the rotating bill and having its movement with the bill limited by the frame.
10. The combination, with the frame, of a rotary tying bill having a movable jaw coactive therewith to grip a strand, means to rotate the bill, and a cam for controlling said jaw friction-rotated by and with the rotating bill and having its movement with the bill limited by the frame.
11. The combination, with the frame, of a rotary tying bill having a movable jaw coacting therewith to sever a strand, means to rotate the bill, and a cam for controlling said jaw friction-moved by and with the rotating bill and having its movement with the bill limited by the frame.
12. The combination, with the frame, of a rotary tying bill having a movable jaw coactive therewith to sever a strand, means to rotate the bill, and a cam for controlling said jaw friction-rotated by and with the
- strands against said checks and affording clearance to each strand to be displaced laterally under the check for the other strand.
13. In combination, two strand-gripping structures each having means to grip both strands, and strand-tying means operative on the strands between the strand-gripping portions of said structures.
14. In combination, two strand-gripping structures each having means to grip both strands and also having means guiding yarns entered therein to form a cross in the strands as a consequence of entering the yarns into the device, and strand-tying means operative on the strands at the cross.
15. In combination, two strand-gripping structures, each having means to grip both strands and one movable in the other, and strand-tying means carried by one of said structures and operative on the strands between the strand-gripping portions of said structures.
16. In combination, two strand-gripping structures each having means to grip both strands and also having means to form a cross in the strands and one movable in the other, and strand-tying means carried by one of said structures and operative on the strands at the cross.
17. In combination, a supporting structure, another structure movable in the first structure, one of said structures having means to grip the material to be tied, tying means movable in the other structure, and means to transmit movement from the movable structure, on movement thereof, to the tying means.
18. In combination, two strand-gripping structures, one movable in the other, strand-tying means carried by one of said structures and operative on the strands between the strand-gripping portions of said structures, and means, actuated by the movable structure on movement thereof, to actuate the tying means.
19. In combination, two strand-cross-forming structures, each having means to grip both strands and one movable in and relatively away from the other, and strand-tying means carried by one of said structures.
20. In combination, two strand-cross-forming structures each having means to grip both strands and one movable in and relatively away from the other, and strand-tying means, carried by one of said structures and operative on said strands at the cross.
21. In combination, two strand-cross-forming structures, one movable in and relatively away from the other and having means to hold and pull on both strands during its movement, and strand-tying means carried by the other of said structures.
22. In combination, two strand-cross-forming structures, one movable in and rela-

tively away from the other and having means to hold and pull on both strands during its movement, moving strand-tying means carried by the other of said structures, and means to synchronize the movements of the movable structure and said tying means.

23. In combination, a supporting structure, a strand-pulling structure movable in the supporting structure and having means to clamp both strands and a tying bill rotative in said supporting structure on an axis extending transversely of the path of movement of said movable structure and having its free end turned off.

24. In combination, a supporting structure, a strand-pulling structure movable in the supporting structure and having means to hold and pull on both strands, said structures having means to form a strand-cross between them, and a tying bill rotative in said supporting structure on an axis extending transversely of the path of movement of said movable structure and having its free end turned off and arranged to rotate in an orbit bisecting the cross.

25. In combination, a crotched structure, another crotched structure movable in the first structure to and from the same, the crotches of said structure being substantially opposed when the movable structure approaches the first-named structure and said crotches being then adapted to receive the strands to be joined, and tying means arranged on one structure, the other structure having means to hold and pull on the strands.

26. In combination, a crotched structure, another crotched structure movable in the first structure to and from the same, the crotches of said structure being substan-

tially opposed when the movable structure approaches the first-named structure and said crotches being then adapted to receive the strands to be joined, tying means arranged on said first-named structure, and means to actuate the tying means from the movable structure on movement of the latter.

27. A knotter having therein strand-cross-forming instrumentalities, comprising, in combination, tying means acting in relation to crossed strands to form a cincture adapted to be upset into a knot, and guides relatively stationary in respect to said tying means when the strands are being acted upon to be tied adapted positively to position each of a plurality of strands, severally entered in the guides under tension, in crossing relation each to the other.

28. A knotter for tying weavers' knots having therein means for forming a preliminary crossing between strands to be tied together, said means comprising strand-guides adapted when relatively stationary to position strands entered therat in crossing relation upon mere tension applied to the strands, in combination with tying means adapted to work on one or more of the strands in relation to the crossing so formed.

29. A knotter for weavers' knots having therein strand-guides adapted on mere entrance therein and tension upon strands applied thereto by the operator the said guides being stationary in respect to the knot forming means to arrange the strands in preliminary relation, in combination with knot-forming means constructed and arranged to operate upon the positioned strands to form the knot.

In testimony whereof I affix my signature.
ROBERT W. BARKER.
